[57] **CLAIM**

The ornamental design for a pair of spectacles without earstems, as shown and described.

DESCRIPTION

FIG. 1 is a front perspective view of a pair of spectacles without earstems showing our new design, the broken line showing of the earstems is for illustrative purposes only and forms no part of the claimed design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and,

FIG. 6 is a bottom plan view thereof.
